UNITED STATES PATENT OFFICE

HENRY R. McCLEARY, OF OAK PARK, ILLINOIS, ASSIGNOR TO WILSON-JONES CO.,
A CORPORATION OF MASSACHUSETTS

PAMPHLET LOOSE LEAF FILE

Application filed July 2, 1927. Serial No. 203,042.

This invention relates to a pamphlet binder and concerns itself with means for confining the extra wire rods which usually form part of the equipment of such a binder and the manner of securing the impaling means.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is an end elevational view of a pamphlet binder involving this invention;

Figure 2 is an enlarged sectional view taken upon the line II-II of Figure 1;

Figure 3 is a fragmentary plan view of the interior of the binder with the pamphlets removed;

Figure 4 is an enlarged fragmentary sectional view taken upon the line IV-IV of Figure 2;

Figure 5 is an enlarged fragmentary sectional view taken upon the line V-V of Figure 4.

In the present embodiment of this invention there is shown a binder comprising a one-piece cover member 1 to which a sheathed back plate 2 is secured by suitable tangs 3. The back plate is of arcuate formation in cross-section whereby the back of the book will likewise be of arcuate formation in cross-section. Extending longitudinally of the central interior part of the cover and in parallel relation with the sheathed back plate

2 there is a sheet-metal casing 4 which is secured by the formation tangs 3 of the back plate. The sheet-metal casing 4 is substantially elliptical in cross-section and it may consist of a bowed lower plate 5 and a convex upper cover plate 6 which has its lateral

margins crimped around the upper margins of the lower plate 5.

The casing 4 is provided with a pair of spaced notches 7 a short distance from each end of the binder through which wire loops 8 extend. Within the casing the wire loops are offset as indicated at 9. At the beginning of the offset portions as indicated at 10 (Figure 5) there is a substantial bearing against the casing. This particular structure of the loops maintains the same in proper upright position against rotation. It will be noted that the upper corners 8a are relatively sharp for the purpose of facilitating the assembly of the pamphlets as will later more fully appear.

Spaced inwardly from each end of the upper plate 6 there is stamped downwardly a depression 11. The ends of the sheet-metal casing 4 are closed by end plates 12 which have shanks 13 extending within the casing. These shanks terminate in narrow resilient tongues 14. The inner end of each tongue 14 is provided with a V-shaped notch 15 shown more clearly in dotted lines in Figure 3. The tongues 14 are upwardly offset with relation to the shanks 13 as shown in Figure 2. The aforementioned depressions 11 are adapted to engage in notches 15 of the tongues 14 for removably locking the end plates in position. The purpose of these removable end plates or end closures 12, as they are sometimes called, is to afford access to the extra wires 16 which are adapted to be carried in the casing. The end closure plates 12 also serve to prevent the wires from slipping out of the loops 8 when only a few pamphlets are in the binder.

This binder is adapted for containing pamphlets 17 which are suitably notched at their bound edges to fit over the wire loops 8, as shown in Figure 4. They are retained in such position by the thin wires 16 which extend through the folds of the pamphlets. Such pamphlets are frequently current pub-

lications which are issued periodically and they are adapted to be filed in the binder as just explained. The extra wires necessary for adding pamphlets are, of course, retained in the casing 4 and in order to have access to these wires it is merely necessary to depress the tongue 14 of one of the end closures by inserting a pencil or tool through the notch 18 which is formed adjacent the aforementioned depression 11. As the tongue 14 is depressed the tongue 11 on the plate 6 will become disengaged from the V-shaped notch 15 and allow the end plate to be withdrawn in order that a wire may be withdrawn from the casing.

It will be appreciated that by confining the extra wires in the casing the binder may be tossed about as desired without displacement or loss of any of the extra wires. Further, in handling, it is impossible for them to fall from the casing as would happen if such extra wires were merely retained in an open sheath on the inside cover of the binder as has been the practice in some instances. It will also be appreciated that by offsetting the wire loops 8 within the casing, as previously explained, there is no likelihood of their becoming loose or rotating. Further, the sharp corners or bends 8a in the loops greatly facilitate the insertion of the wires 16, especially when the binder is getting full, since such sharp corners will project further through the notches in the book and provide more space for the insertion of the wires.

I am aware that many changes may be made, and numerous details of construction may be varied through a wide range without departing from the principles of this invention, and I therefore do not purpose limiting the patent granted hereon, otherwise than necessitated by the prior art.

I claim as this invention:

1. In a pamphlet binder, a casing having downwardly struck depressions, and end closures having resilient tongues provided with notches for engaging said depressions.

2. In a loose leaf binder, a casing having a downwardly extending depression, and end closure for said casing having a resilient tongue provided with a notch for engaging said depression.

3. In a pamphlet binder, a cover member, a longitudinally extending casing in said cover member and a cap having a resilient tongue extending into said casing; said tongue and the top of said casing having mutually engageable interlocking parts, adapted to be unlocked by a downward pressure on said tongue said casing having an aperture above said tongue.

4. In a pamphlet binder, a longitudinally extending casing having notches, and wire loops extending thru said notches, each wire loop having offset portions adjacent its ends

bearing against opposite portions of the interior of the casing to prevent rocking movement of said loops.

5. In a pamphlet binder, a casing double convex in cross-section and having apertures therein, and wire loops extending thru said apertures, each wire loop having parts adjacent each end bearing along opposite portions of said casing adjacent each aperture for the purpose set forth.

In testimony whereof I have hereunto subscribed my name at Chicago, Cook County, Illinois.

HENRY R. McCLEARY.
